UNITED STATES PATENT OFFICE.

SYLVESTER CLEYON GOODRICH, OF WELLSTON, OHIO.

DESIGN FOR A TRAFFIC GUIDEPOST.

Application filed March 9, 1925. Serial No. 12,642. Term of patent 3½ years.

To all whom it may concern:

Be it known that I, SYLVESTER CLEYON GOODRICH, a citizen of the United States, residing at Wellston, in the county of Jackson and State of Ohio, have invented a new, original, and ornamental Design for Traffic Guidepost, of which the following is a specification, reference being had to the accompanying drawing, forming a part hereof.

The figure is a perspective view of a traffic guidepost, showing my new design.

What I claim is:

The ornamental design for a traffic guidepost, as shown.

SYLVESTER CLEYON GOODRICH,
